BALL CATCHER TOY

Harold E. Hasselbusch, 144-23 68th Drive,
Flushing, N.Y.

Filed Aug. 28, 1961, Ser. No. 66,509

Term of patent 14 years

(Cl. D34—5)

FIG. 1 is a side elevational view of a ball catcher toy showing my new design;

FIG. 2 is a bottom plan view thereof, a portion of the handle being cut away for convenience of illustration, the appearance of the handle being the same on the top and bottom sides; and

FIG. 3 is a top plan view thereof.

I claim:

The ornamental design for a ball catcher toy, as shown and described.
